A. P. LOHMANN.
ANCHOR FOR CONCRETE WORK.
APPLICATION FILED DEC. 23, 1913.

Patented Sept. 15, 1914.

1,110,806.

UNITED STATES PATENT OFFICE.

ALFRED P. LOHMAN, OF AKRON, OHIO.

ANCHOR FOR CONCRETE WORK.

1,110,806.

Specification of Letters Patent. Patented Sept. 15, 1914.

Application filed December 23, 1913. Serial No. 808,311.

To all whom it may concern:

Be it known that I, ALFRED P. LOHMAN, a citizen of the United States, residing at Akron, in the county of Summit and State of Ohio, have invented new and useful Improvements in Anchors for Concrete Work, of which the following is a specification.

This invention relates to improvements in anchoring devices adapted to be embedded 10 in cementitious structures, such for instance, as concrete, and is of the general type shown in U. S. Letters Patent to me March 1, 1913, No. 950,771.

The primary object of this invention is to 15 so form the device that its engagement with the body of the material in which it is enclosed will be more effectual than the type of device shown in my patent heretofore referred to.

20 A further object is to so construct the device as to permit the placement of transverse and longitudinal reinforcing bars in the cementitious material without interference with the anchor and also so constituted 25 that the anchor itself will serve as a supporting medium, if desired, for the reinforcing bars or rods in the concrete for holding them in spaced relation with respect to the form in which the concrete is placed.

30 With the foregoing and other objects in view, the invention consists in the novel construction, combination and arrangement of parts constituting the invention to be hereinafter specifically described and illustrated 35 in the accompanying drawings which form a part hereof wherein is shown the preferred embodiment of the invention, but it is to be understood that changes, variations and modifications can be resorted to which come 40 within the scope of the matter hereinafter claimed.

In the drawings in which similar reference numerals indicate like parts in the different figures, Figure 1, is a perspective view 45 of an anchor embodying this invention; Fig. 2, is a view in side elevation of the device shown in Fig. 1; Fig. 3, is a section of a concrete structure with my improved anchor positioned therein, the section being taken 50 transversely of the longitudinal line of the

anchor; and, Fig. 4, is a perspective view of a member commonly employed in connection with the anchor.

Referring more particularly to the drawings the reference numeral 1 denotes the 55 body of the anchor which is preferably in the form of an inverted frustum of an elongated pyramid with inwardly and downwardly sloping exterior walls 2 and with the inner faces 3 thereof inwardly inclined and 60 usually approximately parallel with the outer walls 2.

The side walls 2 are provided with lugs 4, 5 and 6 on each side, the lugs on each side being spaced from each other to provide 65 notches 7 through which nails or other hold-fast devices are passed for holding the lower face of the body 1 against one of the walls of the form in which is placed the concrete. The body 1 being hollow provides an interior recess 8 the edges 9 of which are adapted to lie approximately flush with the inner face 10 of the cementitious structure 11. The body portion is adapted to be placed in the cementitious structure while it is in a 75 plastic condition and as the structure hardens it becomes firmly embedded and is thereby anchored. Positioned within the recess 8 is a member 12 preferably in the form of an inverted frustum of a pyramid provided 80 with an aperture 13 through which is passed a supporting rod 14. Any structure, such for instance, as a gas pipe or shaft, is secured to the supporting medium 14 and the wedging action developed by engagement of 85 the structure with the wall causes the member 12 to wedge itself accurately in position against the inclined inner faces in the body 1.

The device so far described is to all intents and purposes approximately identical 90 with that shown and described in my patent hereinbefore referred to.

Extending upwardly from opposite the ends 15 and 16 of the body portion 1 and preferably on opposite sides thereof are a 95 pair of prongs or anchoring members 17. These members 17 preferably extend laterally beyond the normal outlines of the side edges 2 of the body 1 and are preferably inwardly-bent to provide hooked ends 18 100

turned toward each other and with their termini approximately in longitudinal alignment with each other. These prongs or anchoring members 17 are preferably constructed with reinforcing ribs 19 for strengthening purposes.

As the members 17 project laterally and the points 20 thereof extend beyond the normal outlines of the body 1, they thereby increase the area or width of the breaking lines of concrete, which are usually at an angle of 45° with respect to the vertical line of the body, and these breaking lines are indicated by the dotted lines 21 in Fig. 3, so that by so forming the members 17 as shown, the area covered is greater than the body 1 of the anchor, and hence, a better grip or bond is formed with respect to the concrete and the anchorage thus secured is capable of sustaining a greater load.

In Fig. 3, wherein the view is taken in section transversely of the median line of the anchor, one member 17 is shown in heavy dotted lines, and the position of the opposite member 17, which is removed by reason of the section, is indicated by light dotted lines 22, solely to show its relation with respect to the heavy dotted lines of the member 17.

Aside from the superior amount of anchorage obtained by a device of this character, the positioning of the members 17 at opposite ends of the body 1 permits the placement of transverse reinforcing bars 23 in the material without interfering with the anchor body 1. Longitudinal reinforcing bars 24 may be also placed in the concrete without any interference with the body 1.

Customarily, in placing bars in reinforcing concrete structures, the bars are placed where the stress occurs, and as necessity compels their placement they have seriously interfered with the embedding of anchors of this general type in the concrete for the reason that the anchors afford an obstruction to the placement of the bars. But in this construction the anchor may be placed anywhere desired, such for instance, as centrally on a beam, and the reinforcing rod or bar in the concrete may be placed immediately over the anchor and passed between the two prongs 17 thereof either transversely or longitudinally of the anchor body.

Usually in preparing concrete beams or structures, means must be provided for supporting the strengthening rods embedded therein during the pouring or placement of the concrete material, and the means employed must be sufficiently strong to firmly hold the rods against displacement by the mass of material poured into the form, and hence, if desired, the anchors are secured to the form by hold-fast devices passed

through the notches 7 and the reinforcing bars are laid either transversely or longitudinally on top of the anchors which serve to support the rods or bars during the placement of the concrete. After the removal of the forms, the projecting hold-fast devices 70 which have been passed through the notches 7 are cut off and the under face of the anchors are flush with the concrete structure, as shown in Fig. 3.

It will be noted that the body portion 75 when positioned and supporting a reinforcing bar in the concrete constituting a supporting element for this purpose irrespective of whether the bars are extended longitudinally or transverse with respect to the body portion, and hence, for convenience of description, the device constitutes a "chair" for performing this function.

I claim:—

1. An anchoring device for the purpose 85 set forth comprising a body portion adapted to be secured in a concrete structure and with its lower face approximately flush with the face of the wall of said structure, said body portion provided with a pair of upwardly and outwardly-projecting prongs positioned on opposite sides of said body portion and at opposite ends, said prongs projecting outwardly both laterally and longitudinally beyond the normal outlines of 95 said body.

2. An anchoring device for use in connection with concrete structures comprising a body portion adapted to be positioned in a structural self-hardening material with 100 one face thereof approximately flush with the surface of said material, said face provided with a recess extending in said body portion and with the faces adjacent to the opening thereof inclined to constitute a seat 105 for a shiftable member, a member with the sides thereof each provided with inclined faces at an angle to each other, whereby said member may be seated on the inclined faces of said recess, said body portion further provided with a pair of upwardly and outwardly-projecting prongs positioned on the opposite sides of said body portion and at opposite ends thereof, said prongs projecting outwardly both laterally and longitudinally beyond the normal outline of said body portion.

3. An anchoring device for the purpose set forth comprising a body portion provided with a recess in its lower face, the 120 side walls of said recess inclining toward the lower face of the body portion and also inclined toward each other to constitute a wedge-shaped abutment, a coupling member provided with inclined side faces arranged in said recess and to seat on the inclined side wall of said body portion, whereby said member is wedged between said walls when

supporting an object, said body portion further-more provided at its upper portion with a pair of upwardly and outwardly-projecting prongs positioned on opposite sides of said body portion and at opposite ends thereof, said prongs projecting outwardly both laterally and longitudinally beyond the normal outlines of said body portion.

In testimony whereof I have hereunto set my hand in presence of two subscribing ¹⁰ witnesses.

ALFRED P. LOHMAN.
